TOBACCO PIPE

Robert E. Sadlier, Ridley Park, Pa.

Application January 4, 1944, Serial No. 516,903

8 Claims. (Cl. 131—216)

This invention relates generally to the class of tobacco and pertains particularly to improvements in the various forms of smoking, more especially in the present application to pipe smoking.

The various forms of smoking, such as cigars, cigarettes, and pipes all involve the disadvantageous features of "re-smoking," by which is meant a burning of collected, condensed material resulting from the combustion of the tobacco, after the burning of the body of tobacco has maintained for a while.

This condition is brought about as follows:

In pipe smoking, for example, the normally formed products of combustion, such as water, carbon dioxide, tars, essential oils, etc., are drawn through the charge of unburned tobacco to the bottom of the pipe bowl and then up through the stem to the mouth of the smoker. Such normal products are formed from the burning of the fresh tobacco and produce a pleasant and agreeable smoke. However, in passing through the tobacco charge they become absorbed in part and form a progressively thickening or soggy mass and, as the smoking progresses, are reburned, producing disagreeable and undesirable decomposition products. Such products become increasingly more disagreeable as the smoking continues until the tobacco mass becomes so moist or soggy that the pipe can no longer be kept lighted.

As will be readily understood two conditions bring about this moist condition. First, the moisture produced by the normal combustion in being drawn through the tobacco is absorbed thereby until the tobacco becomes saturated and, secondly, after saturation obtains, the moisture still being produced by the combustion, condenses in the stem of the pipe and flows back into the pipe bowl, unless some provision is made for its removal, which in the majority of pipes is not the case. Even if provision is made to prevent this back flow, it will not eliminate the formation of moisture by the combustion or its absorption by the tobacco to the point of saturation as it is drawn through the tobacco, with the resultant "re-smoking" and generation of disagreeable decomposition products.

While reference has been made particularly to pipe smoking and the disagreeable results of drawing the products of combustion through the tobacco charge, it will be readily recognized how the same action will occur in the smoking of cigars and cigarettes, although possibly not to the same extent.

The principal object of the present invention is to provide a smoking device by which the above described undesirable "re-smoking" effect is avoided and the smoker is assured of a fragrant and sweet "smoke."

A further object of the present invention is to provide a smoking device which is constructed in a novel manner whereby the products of combustion are removed before they have had a chance to pass through any considerable amount of the unburned tobacco, whereby condensation of the products or an appreciable portion thereof is avoided.

Still another object of the invention is to provide an improved and novel smoking device which is so constructed that the smoke bearing the products of combustion is immediately drawn away from the unburned tobacco to pass to the mouth of the smoker without losing any part thereof by condensation in the tobacco, whereby the smoker is assured of a sweet "smoke" by reason of the fact that the tobacco remains in its original condition and the described "re-smoking" action cannot occur.

The invention as applied to a smoking pipe will be best understood from a consideration of the following detailed description taken in connection with the accompanying drawing, it being understood, however, that the invention is not to be confined to a strict conformity with the showing of the drawing but may be modified within the scope of the appended claims.

In the drawing:

Figure 1 is a view in side elevation of a pipe constructed to illustrate one manner of carrying out the present invention.

Figure 2 is a vertical, longitudinal section through the bowl and a portion of the stem of the pipe of Figure 1, showing the adjustment for drawing products of combustion off from the upper part of a burning tobacco charge.

Figure 3 is a section corresponding to Figure 2, and showing the adjustment for drawing products of combustion off from the bottom of a tobacco charge.

Figure 4 is a section taken on line 4—4 of Figure 2.

In carrying out the present invention as applied to a smoking pipe there is shown in the drawing, in Figure 1, a smoking pipe which is generally designated P and which comprises the usual bowl 10 and stem 11.

As is shown in Figures 2 and 3 the lower part of the bowl has formed therein a relatively narrow vertical port 12 which is tapered outwardly

and downwardly to open at the constricted end thereof into the bore 13 of the pipe stem. The port 12 is of rectangular cross section in a vertical plane as can be seen from Fig. 4. This port extends across the angle between the bottom part of the pipe bowl and the stem and the bottom wall or floor of the port is substantially straight and forms a continuation of the bottom 14 of the tobacco chamber of the pipe bowl.

Fitted into the port 12 is a valve plug 15 which is of a width to snugly engage between the sides of the port but is of less height than the port. The inner side of this plug is curved or shaped to conform to the shape of the tobacco chamber as indicated at 16. The valve plug is likewise of rectangular cross section in any vertical plane therethrough and its width is approximately the same as that of the port 12 so as to have a close fit therein, as shown in Fig. 4. Also, as is shown in Figures 2, 3, and 4, the height of the valve plug is considerably less than that of the port 12, taken in the same vertical plane. Thus it can be seen that the valve plug is adapted for sliding movement in the port 12.

Connected with the top part of the plug 15 by the swivel 17 is an adjusting screw 18 which is threaded in the bowl of the pipe and extends through the portion between the bowl and the stem to the outside, the axis of the screw being positioned at an angle of 45° with respect to both the axis of the bowl and the axis of the stem. On its outer end the screw has a head 19 by which it may be rotated. Through the medium of the screw the plug 15 can be raised from seated position upon the bottom of the port 12 as it is shown in Figure 2, to raised position against the top wall of the port as shown in Figure 3. Since, as previously stated, both the port 12 and the valve plug 16 are of rectangular shape and the latter is of lesser height than the former, when the valve plug is in seated position there will be formed above same an opening of rectangular cross section comprised by the upper end and side walls of the port 12 and the top edge of the valve plug; likewise when the valve plug is in raised position there will be formed below same an opening of rectangular cross section comprised by the lesser end and side walls of the port 12 and the bottom edge of the valve plug.

When the plug is in the lowered position in which it is shown in Figure 2, there is formed the oblique smoke passage 20 which leads from substantially the transverse center of the tobacco chamber into the bore 13 while, when the plug is in fully raised position as shown in Figure 3, this passage is closed and there is formed the bottom smoke passage 21 which leads directly from the bottom of the tobacco chamber into the end of the bore. Again by virtue of the rectangular cross sectional shapes of both the port 12 and the valve plug 16, as previously described, it will be seen that both the upper smoke passage 20 and the bottom smoke passage 21 are likewise of rectangular cross sectional shape.

With the arrangement shown in Figures 1 to 4, inclusive, it will be seen that when the pipe bowl is filled and ready for smoking, if the plug 15 is in the lowered position as it is shown in Figure 2 and as it should be, the smoke and products of combustion will be drawn off from the bowl after passing through only the upper half of the tobacco charge instead of passing through the entire mass of tobacco as it does in a pipe

of the usual form. In this way the smoke is drawn off before any material quantity of moisture and other products of combustion are formed.

- 5 After the fire level has reached the upper end of the passage 12 then the plug 15 is raised to the position shown in Figure 3 so as to produce the bottom smoke passage 21, through which the smoke may pass into the bowl. Such condensed matter as may have formed in the upper part of the tobacco charge will then be left behind and the smoker will have an entirely fresh quantity of tobacco to smoke in the lower half of the bowl.
- 10 From the foregoing it will be readily apparent how the invention may be satisfactorily applied to a smoking pipe whereby there will be avoided the development of the undesirable and disagreeable conditions attendant upon the smoking of a pipe of the usual or ordinary construction where all of the smoke passes through the entire underlying body of tobacco. There is also avoided the necessity of using the various contrivances which have been devised for preventing the drawing into the mouth through the pipe stem of fluids which usually collect in the bottom of the bowl.

I claim:

1. A smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl and means for moving the first named means.

2. A smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl and means for moving the first-named means, said last-named means having a screw-threaded relation with one of said first-named members.

3. In a smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl and means for moving the first-named means, said last-named means having a screw-threaded relation with one of said first-named members, one of said openings being substantially axially and the other substantially inclined to the bore in the stem member.

4. A smoking pipe having a bowl member and tubular stem member, said bowl member having

a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl and means for moving the first-named means, said passageway being substantially rectangular in cross-section.

5. In a smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl, the openings formed by the first-named means and the bowl member and the stem member being substantially rectangular in cross-section, and means for moving the first-named means.

6. A smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl and means for moving the first

named means in a direction at substantially 45° to the axis of the bowl member.

7. A smoking pipe having a bowl member and tubular stem member, said bowl member having a tobacco holding cavity and said stem member having a bore, a passageway between the cavity and bore, means within the passageway having one part thereof constituting a portion of the wall of the cavity and adapted to be moved to provide the mouths of openings at different levels to permit smoke to pass from the cavity to the bore whereby smoke can be drawn in by-passing relation with an unburning portion of the tobacco in said bowl, the openings formed by the first-named means and the bowl member and the stem member being substantially rectangular in cross-section, and means for moving the first-named means.

8. A tobacco pipe comprising a bowl and a tubular stem, the bowl having a tobacco holding cavity and provided with a tapered opening leading directly from the lower portion of the cavity into the stem, the opening having greater height at the cavity side thereof than at the stem side, a plug of substantially corresponding configuration to the opening positioned in the opening for limited movement therein, one portion of the plug at all times constituting a portion of a wall of the cavity, and means connected with the plug and accessible outside of the pipe bowl for shifting the plug into either of two positions in the opening, the plug when in one position forming with a wall of the opening a passage leading from the bottom of the bowl into the stem and when in its other position forming an opening leading into the stem from the upper part of the bowl.
